[57] CLAIM

The ornamental design for fingernail polishing tool, substantially as shown and described.

DESCRIPTION

FIG. 1 is a top plan view of a fingernail polishing tool showing our new design;

FIG. 2 is a front elevational view thereof;

FIG. 3 is a bottom plan view thereof;

FIG. 4 is a left side elevational view thereof;

FIG. 5 is a right side elevational view thereof; and

FIG. 6 is a perspective view thereof.

The rear is a mirror image of the front.

A rear view is omitted since it is symmetrical with a front view thereof. The function of this design is as follows. This tool is used in polishing fingernails. That is to say, a ring is attached to one end of a block and after inserting a finger into the ring, the surface of a given nail is carefully rubbed by a soft buff member attached to one side of the block held by hand, so that the surface of the nail may be smoothed and polished.
